UNITED STATES PATENT OFFICE.

JOHN W. FARLEY, OF CLEVELAND, OHIO.

RADIATOR HANGER.

Application filed February 26, 1925. Serial No. 11,783.

My invention relates to improvements in devices for supporting the radiators of heating systems above the floors of the buildings in which they are used, without the necessity of employing legs on said radiators.

One object of the invention is to provide a new and improved form of support which is particularly adapted for use in connection with the walls of buildings formed of tile, brick or blocks, unique provision being made whereby the device may be effectively anchored to the wall.

Another object is to provide new and improved means for connecting the upper end of a radiator with the wall-carried bracket.

A still further object is to provide a device which is of extreme simplicity, may be easily and inexpensively manufactured, may be sold at small cost, may be easily installed wherever desired during the construction of a building, and will be highly efficient and in every way desirable.

With the foregoing in view, the invention resides in the novel subject matter herein-after described and claimed, the description being supplemented by the accompanying drawings.

Figure 1 is a vertical transverse sectional view through a radiator, a portion of a tile wall, and the improved radiator support.

Figure 2 is an inner side or front elevation of the parts shown in Fig. 1, a portion of the radiator being broken away to disclose the support behind it.

Figure 3 is a horizontal sectional view taken substantially on the plane of line 3—3 of Fig. 1.

Figure 4 is a perspective view of the complete hanger.

Figure 5 is an enlarged plan view of parts of the means for anchoring the upper end of the radiator.

In the drawings above briefly described, illustrating the preferred form of construction, the numeral 1 designates in a general way a bracket which is adapted to be anchored to a wall, the bracket being intended primarily for use in connection with a wall formed of tiles T, although it is usable also in connection with walls constructed from brick, cement blocks, etc. In the preferred construction, the bracket 1 is formed from a single metal bar whose main, intermediate portion 2 is disposed vertically and is provided near its upper end with a vertical slot 3. At the upper end of the

vertical portion 2, the bar is horizontally directed as indicated at 4 and formed with an opening 5. Then, the bar is upwardly extended as indicated at 6 to contact with the inner side of a tile or the like, and from this portion 6, said bar is extended again in a horizontal direction as indicated at 7, to lie upon said tile or the like. This portion 7 is provided with a hooked, vertically directed terminal 8 which engages the outer side of a tile or other wall unit to prevent said portion 7 from withdrawing from the wall, and the flat formation of the portion 7 prevents the bracket from swinging in a plane parallel with the wall, as said portion is tightly held in the masonry.

The lower end of the metal bar is laterally directed to engage the inner side of the wall, and in the preferred form of construction, this end extends rearwardly and downwardly as indicated at 9 and is provided with a lower extremity 10 which is adapted to bite into one of the mortar joints 11 between adjacent tiles or the like. The portion 9 of the bracket thus serves to space the lower end of the vertical portion 2 inwardly or forwardly from the wall and as said portion 9 thrusts downwardly upon the mortar joint 11 or a corner of the tile or the like under this joint, it assists materially in carrying the weight of the radiator. The upper end of the vertical bar portion 2 is, of course, spaced from the wall by the formation 4—6, so that said portion can only assume a truly vertical position.

A radiator-supporting hook 12 is provided to engage the lower end of a radiator, as shown. This hook is provided with a vertical shank 13, the major portion of which is disposed at the outer or front side of the vertical bar portion 2, below the slot 3. The upper end of the shank 13, however, is offset as indicated at 14 and passes through the slot 3, and then upwardly through the opening 5 of the horizontal portion 4, said offset upper end of the shank being provided with a nut 15 or other shoulder over the horizontal bar portion 4, to carry the weight of the radiator. This shoulder 15 is preferably in the form of a nut to obtain any desired vertical adjustment of the hook 12 and the radiator supported thereby.

At 16, a horizontal bar or rod is shown, having a hook 17 to engage the rear side of the upwardly projecting end of the shank 13, said hook being preferably interposed

between the nut 15 and the horizontal portion 4 of the bracket-forming bar. Provision is made for clamping the upper end of the radiator against the rod 16, such provision preferably comprising an eye-bolt 18 and a U-shaped clamping member 19. The eye 20 of the bolt 18 is slideable along the rod 16, so that said bolt may be passed forwardly between two of the sections of the 10 radiator. Then, the clamping member 19 is placed on the bolt between said radiator sections and finally the nut 21 is threaded into place. By thus clamping the upper end of the radiator to the rod 16, and providing the latter with the hook 17 engaging the upper end of the shank 13, it will be seen that said upper end of the radiator is effectively anchored. Preferably, a portion 15 22 of the rod 16 extends obliquely from and beyond the hook 17 to bind against one edge of the vertical bar portion 7, thus effectively stabilizing the rod and the radiator and preventing them from having a tendency to swing about the shank 13 and a pivot. The 20 25 opposite end of the rod 16 may well be laterally bent as indicated at 23, to prevent accidental sliding of the eye 20 from said rod, before the device is installed.

By providing the novel construction shown and described, the objects of the invention are effectively carried out, and while this construction is preferable, it is to be understood that within the scope of the 30 35 invention as claimed, modifications may be made.

I claim:

1. A radiator supporting bracket comprising a main vertical portion, a flat upper end portion integral with and directed horizontally from said main portion and adapted to lie upon a tile, block, or brick forming part of a wall, the outer extremity of said horizontal end portion being vertically directed to prevent withdrawal from the wall, 40 45 and a lower end portion directed laterally from the lower end of said vertical portion and adapted to engage the wall.

2. A radiator supporting bracket comprising a main vertical portion, a flat upper end

portion directed horizontally from said main portion and adapted to lie upon a tile, block, or brick forming part of a wall, the outer extremity of said horizontal end portion being vertically directed to prevent withdrawal from the wall, and a lower end portion projecting laterally and downwardly from the lower end of said vertical portion and having a terminal adapted to bite into a horizontal mortar joint of the wall, thereby assisting in carrying the weight of the 60 radiator and also spacing the lower end of the aforesaid vertical portion from the wall.

3. A radiator supporting bracket comprising a flat metal bar having a vertical intermediate portion, said bar having its upper end portion bent horizontally then upwardly and then again horizontally, the last named horizontal portion being adapted to rest on a tile, block or brick forming part of a wall and having a vertically bent hooked extremity to prevent withdrawal from the wall, the upwardly extended portion being adapted to abut the inner side of the wall, the lower end portion of the bar being laterally directed to engage the wall, said body 70 75 of the bar having a vertical slot and the first named horizontal portion being formed with an opening, a radiator supporting hook having an upstanding shank whose lower portion is disposed at the front side of said bar, the upper end portion of said shank being rearwardly offset and passing through said slot and said opening, a bar adapted to extend horizontally in rear of a radiator, one end of said horizontal bar having a 80 85 hook adapted to engage the rear side of said shank and to rest on the first named horizontal portion of the first named bar, said horizontal bar being provided with a portion projecting from its hook to engage one edge 90 95 of said upwardly extending portion of the first named bar, said shank being provided with a shoulder adapted to rest on the hook of said horizontal bar.

In testimony whereof I have hereunto af- 95 fixed my signature.

JOHN W. FARLEY.
